BED LAMP

William J. Horner, Piedmont, Calif.

Application January 8, 1935, Serial No. 891

2 Claims. (Cl. 240—4)

My invention relates to improvements in bed lamps, and it consists of the combinations, constructions and arrangements hereinafter described and claimed.

5 An object of my invention is to provide a bed lamp which has means for directing the light to either side of a bed and for controlling the amount of light so that one of the occupants of a double bed may read, while the other person 10 may sleep, without being annoyed by the light. The device is also designed to give light to both occupants of the bed without illuminating the room to too great an extent. It is also possible to enlarge the light opening of the device so that 15 the entire room can be illuminated. The means for securing the lamp to the bed is adjustable so that the light opening can be changed to different angles, and thus throw the light in the desired direction. It is obvious that the device 20 can be used as a table lamp as well as a bed lamp.

A further object of my invention is to provide a device of the type described which is extremely simple in construction and is durable and efficient for the purpose intended.

25 Other objects and advantages will appear in the following specification, and the novel features of the device will be particularly pointed out in the appended claims.

30 My invention is illustrated in the accompanying drawings forming a part of this application, in which

Figure 1 is a front elevation of the device with portions thereof being broken away;

35 Figure 2 is a section along the line 2—2 of Figure 1;

Figure 3 is an isometric view of a part of the device;

Figure 4 is a front elevation of a modified form 40 of the invention;

Figure 5 is a section along the line 5—5 of Figure 4;

Figure 6 is a section along the line 6—6 of Figure 4;

45 Figure 7 is an isometric view of a part of Figure 4;

Figure 8 is a front elevation of another modified form of the invention, a portion being shown in section; and

50 Figure 9 is a section along the line 9—9 of Figure 8.

In carrying out my invention I provide a cup-shaped end 1, see Figure 1, in which I dispose a split cylindrical shell or casing 2. The casing 55 2 is secured to the end 1 and the split portion

constitutes a window 3 for permitting the light from a lamp 4 to pass therethrough. The lamp 4 is mounted in a socket 5 and the socket in turn is secured to the end 1. An electric wire 6 passes through the end 1 and is electrically connected 5 to the lamp 4 by a pull chain switch 7.

The other end of the casing is closed by a removable cup-shaped end 8 and when this end is in position it defines the right-hand side of the opening 3. Within the casing 2, I rotatably dispose a shutter 9. The shutter is in the shape of a split cylinder and has a length equal to the length of the casing 2. The split portion 10 of the shutter is of the same dimension as the split portion of the casing 2. In other words, when 15 the shutter 9 is rotated so as to align the split portion 10 with the window 3, the window will be entirely opened.

The means for rotating the shutter 9 comprises a wire 11 that has a curved portion equal 20 to the curved portion of the shutter. One end of the wire extends radially and inwardly from the corner 12 of the shutter as shown at 13, and then the wire is bent at 14 so as to coincide with the axis of the shutter 9 and the casing 2. The 25 portion 14 extends through an opening 15 in the end 8 and the portion is threaded at 16 for receiving a handle 17. It will be seen from this construction that the turning of the handle 17 will turn the shutter 9 within the casing 2. 30

When the split portion 10 coincides with the window 3 the greatest amount of light will pass through the window. This light is sufficient to illuminate the room in which the device is used. Figure 3 shows the shutter 9 as being provided with a large central opening 18, and Figure 1 shows this opening in registration with the windows 3. The opening 18 is of such size as to permit sufficient light to pass through the window 3 so that both occupants of the bed can 40 read. This light, however, is not sufficient to illuminate the entire room, and therefore it will be possible for another person in the room, such as a baby, to sleep undisturbed by the light. If it is desired to cut down the amount of light it 45 is only necessary to turn the handle 17 for moving part of the opening 18 beneath the shell 2. In this simple way the amount of intensity of the light issuing from the window 3 can be controlled at will. 50

In addition to the window 18, I provide two smaller openings 19 and 20 in the shutter 9, see Figure 3. The opening 19 can be moved into registration with the window 3, and this opening is of such a size as to project light rays from the 55

right-hand half of the casing 2, shown in Figure 1. This light will be sufficient for a person lying on the right-hand side of the bed to read without causing the other person to be disturbed by the light. The quantity of light issuing from the opening 18 can be controlled by revolving any portion of the opening beneath the casing 2.

If it is desired that the light issue from the left-hand side of the casing and not the right-hand side, the opening or window 20 is brought into registration with the window 3 by the turning of the shutter 9. The intensity of this light can be controlled by moving any portion of the opening 20 beneath the casing 2. In order to direct the light rays forwardly from the openings 18, 19 and 20, I provide the sides of these openings with flanges 21 that stop diagonal rays of light from passing through the openings. It is obvious that the interior of the shutter 9 can be provided with a reflecting surface in order that a greater amount of light will be projected through the various openings when they are used.

The casing 2 is also adjustable, and in Figures 1 and 2 I show hook-shaped supports 22 which are removably connected to a bed 23 and the other ends of the hooks are slidably received in sleeves 24 that are carried by the casing 2. If desired the sleeves can have slots 25 therein through which screws 26 carried by the hooks 22 project. Wing nuts 27 adjustably secure the hooks 22 to the sleeves. It will be seen that the window 3 can be moved into a position to direct the light at the desired angle with this arrangement.

35 In Figures 4 to 7 inclusive I show a modified form of the invention. In this form the shutter 9 is dispensed with and sliding shutters 28 are used. These shutters close the window 3 of the casing 2, and can be extended for providing an opening 29 of any desired size through which the light can pass. It will be seen from Figures 5 and 6 that the window 3 has flanges 30 extending along the top and bottom edges of the window. The shutters are grouped in threes and 45 I provide two sets of shutters as shown in Figure 6. The shutter 28a, see Figure 7, has flanges 31 at its top and bottom designed to receive the flanges 30. In this way the shutter 28a is secured to the casing 2 and closes the end of the window 3 disposed adjacent to the end 1 and the end 8. The shutter 28a is held against movement either by friction, or it may be welded or otherwise secured in place.

The rear surface of the shutter 28a carries top 55 and bottom guides 32 which slidably receive a second shutter 28b. Figure 6 shows how the shutter 28a carries a stop 33 which will engage with a stop 34 carried by the shutter 28b when the latter has been moved into extended position. The third shutter 28c is slidably received in the curved top and bottom edges 35 of the shutter 28b. The second shutter 28b has a stop 36 designed to contact with the stop 37 carried by the shutter 28c. The stops 36 and 37 when 65 contacting with each other limit further movement of the shutter 28c. I have described one group of shutters and the other group is identical in construction, and therefore needs no further description.

70 Figure 4 shows how the three shutters 28a, 28b and 28c of the right-hand group can be extended

for providing the small opening 29 at the left-hand side of the casing 2. Figure 6 shows how both groups of shutters can be extended for positioning the opening 29 at the center of the casing, and for making this opening larger than that shown in Figure 4. In this simple manner the opening 29 can be made of any size up to the limit of the opening movement of the shutters, and can be positioned at any place along the window 3 within the extreme limits provided by the end shutters 28a. It will be seen that the two sets of shutters 28 produce the same result as the shutter 9. The end 8 can be removed when it is desired to insert a new lamp 4 in the socket 5. This is true of the two forms of the device already described, and also is true of the third form which will now be described.

The third form is shown in Figures 8 and 9, and the window 3 in this instance is closed by an 20 arcuate shutter 38. The shutter 38 is of the same length as the window 3, and is slidably received in guide channels 39 which in turn are secured to the casing 2. The shutter 38 may be moved for exposing any desired portion of the window 3, and in this way the light emanating 25 from the window can be controlled.

The arcuate shutter 38 carries three small 30 arcuate shutters 40, 41 and 42. The small shutters are disposed over small windows 43, 44 and 45 provided in the large shutter 38. The large 35 shutter 38 carries guides 46 which slidably receive the shutters 40, 41 and 42.

The openings 43 and 45 function in the same manner as the openings 18 and 20, while the opening 44 takes the place of the opening 18. The large shutter and the small shutters are frictionally held in adjusted position. In the last two forms of the device I have not shown the hook-shaped supporting members 22. In 40 actual practice, however, the supporting members or other equivalent supporting means will be used for the last two forms mentioned.

I claim:

1. A lamp comprising a casing having a window therein extending substantially throughout the length of the casing, a light mounted in the casing, a large shutter equal in length to the window and being slidable over the casing for closing the window to the desired extent, said shutter having openings therein, and small shutters for controlling the amount of light passing through the small shutter openings, said small shutters being designed to entirely close the openings in the large shutter if desired.

2. A bed lamp comprising an elongated casing, means for supporting the casing in a horizontal position, a light in the casing, said casing having an elongated window extending substantially throughout the length of the casing, a large closure for the window equal to the length of the window, said closure being movable across the width of the window for regulating the amount of light issuing therefrom, and for completely closing the window, and a number of small closures carried by the large one and being independently openable for permitting light to issue from different parts of the window, said small closures being adjustable for controlling the amount of light.

70 WILLIAM J. HORNER.
